(57) **CLAIM**

The ornamental design for a hair dryer, as shown and described.

DESCRIPTION

FIG. 1 is a front perspective view of my new design for a hair dryer.

FIG. 2 is a rear perspective view of FIG. 1.

FIG. 3 is a left side elevation view of FIG. 1.

FIG. 4 is a right side elevation view of FIG. 1.

FIG. 5 is front side elevation view of FIG. 1.

FIG. 6 is a rear side elevation view of FIG. 1.

FIG. 7 is a top plan view of FIG. 1.

FIG. 8 is a bottom plan view of FIG. 1.

FIG. 9 is a front perspective view of my new design for a hair dryer. The buttons shown in dotted lines are for illustrative purposes only and are not part of the claimed design.

FIG. 10 is a rear perspective view of FIG. 9.

FIG. 11 is a left side elevation view of FIG. 9.

FIG. 12 is right side elevation view of FIG. 9.

FIG. 13 is a front side elevation view of FIG. 9; and,

FIG. 14 is a bottom plan view of FIG. 9.

The dot-dash lines in the drawing are boundary lines that form no part of the claimed design.
